UNITED STATES PATENT OFFICE.

SYDNEY CROSBIE, OF HERTFORD, ENGLAND.

LIQUID-FUEL BURNER.

1,072,918.

Specification of Letters Patent. Patented Sept. 9, 1913.

Application filed January 6, 1913. Serial No. 740,529.

To all whom it may concern:

Be it known that I, SYDNEY CROSBIE, a subject of the King of Great Britain, residing in Hertford, England, and whose post-office address is the "Chestnuts," New Barnet, in the county of Hertford, England, glass manufacturer, have invented certain new and useful Improvements in Liquid-Fuel Burners, of which the following is a specification.

My invention relates to spray burners for furnaces, using liquid fuel, which burners are of the kind wherein engine driven propellers or fans are used in the carbureting chambers of the burners for atomizing the fuel, and it consists in improvements according to which the burner is associated with means whereby steam is generated by the heat of the furnace and is utilized in driving the fan operating engine and in supplying the water to the steam generator.

I will describe my invention with reference to the accompanying diagrammatic drawing, which is a sectional elevation of the improved carbureting or atomizing apparatus.

The drawing shows at B a sleeve running upon the outside of the liquid fuel or oil feed pipe D, through the gland C, and provided with torsion rods E, E, which are attached to the fan F just behind the nozzle S. This sleeve is driven by means of a belt N and the pulleys M from the shaft T of the steam engine L, the engine being supplied with steam from the reservoir or boiler K fitted with a safety valve O. The nozzle R of the burner H is water jacketed, and is adapted to be arranged within the associated furnace so that it is subjected to the heat thereof. The water in the jacket and in the circulating pipe Q, Q will boil with considerable

vigor, generating steam in the reservoir or boiler K at sufficient pressure to drive the steam engine L to which the steam is delivered by the pipe J. Correlated with the steam engine is a small pump L' which is adapted to supply the reservoir or boiler K with water through the pipe P. Air is supplied to the burner H through the valve G in the direction of the arrow U.

Having thus described the nature of the said invention and the best means I know of carrying the same into practical effect, I claim:

1. In a spray burner for liquid fuel furnaces having a carbureting chamber and a fuel atomizing fan therein, the combination of a steam generator comprising a part integral with the burner nozzle disposed within the furnace end, means adapted to operate said fan and to feed the generator with water and connections operatively connecting the generator and said means.

2. In a spray burner for liquid fuel furnaces having a carbureting chamber and a fuel atomizing fan therein, the combination of a steam generator comprising a water jacket formed in the wall of the burner nozzle, a reservoir and ducts communicating with the jacket and reservoir, a pump adapted to feed the jacket with water, an engine operatively connected with the fan and the pump, and a pipe connecting the reservoir and the engine.

In testimony whereof I have signed my name to this specification in the presence of two subscribing witnesses.

SYDNEY CROSBIE.
